CENTERPIECE

Walter T. Heintze, Elizabeth, N. J., and Ann T. Donahue, New York, N. Y., assignors to Fostoria Glass Company, Moundsville, W. Va., a corporation of West Virginia

Application December 28, 1949, Serial No. 6,863

Term of patent 3½ years

(Cl. D36—2)

To all whom it may concern:

Be it known that we, Walter T. Heintze, a citizen of the United States of America, residing at Elizabeth, in the county of Union and State of New Jersey, and Ann T. Donahue, a citizen of the United States of America, residing at 51 W. 10th St., N. Y., in the county of New York and State of New York, have invented a new, original, and ornamental Design for Centerpiece, of which the following is a specification, reference being had to the accompanying drawings, forming a part thereof, wherein:

Fig. 1 is a side elevational view of a centerpiece showing our new design;

Fig. 2, another side elevational view, viewed from a different direction, the bowl portion being illustrated in section to disclose the cross sectional contour thereof;

Fig. 3, a horizontal sectional view taken on the line 3—3 of Fig. 2, looking in the direction indicated by the arrows;

Fig. 4, an elevational view of the upper portion

of the centerpiece, viewed from a direction opposite to that of Fig. 2; and,

Fig. 5, also an elevational view of the upper portion of the centerpiece but viewed from a direction opposite to that of Fig. 1.

We claim:

The ornamental design for a centerpiece, as shown.

WALTER T. HEINTZE.
ANN T. DONAHUE.
